(57) **CLAIM**

The ornamental design for a band for holding a fashion article as shown and described.

DESCRIPTION

FIG. 1 is a front perspective view of a band for holding a fashion article showing our new design.

FIG. 2 is a rear perspective view thereof.

FIG. 3 is a front view thereof, the rear view being identical.

FIG. 4 is a left side view thereof.

FIG. 5 is a right side view thereof.

FIG. 6 is a top view thereof.

FIG. 7 is a bottom view thereof; and,

FIG. 8 is a front view thereof shown in use in a reduced scale.

The long dash-short dash broken lines represent unclaimed boundary lines.

The stippled patterns represent contour. The evenly spaced broken lines depict environmental elements that form no part of the claimed design.
